UNITED STATES PATENT OFFICE.

LYMAN R. SWETT, OF BOSTON, MASSACHUSETTS.

CONTRIBUTION ENVELOPE.

1,412,496.

Specification of Letters Patent. Patented Apr. 11, 1922.

Application filed May 26, 1921. Serial No. 472,682.

To all whom it may concern:

Be it known that I, LYMAN R. SWETT, a citizen of the United States, residing at the city of Boston, county of Suffolk, State of Massachusetts, have invented new and useful Improvements in Contribution Envelopes, of which the following is a specification.

This invention relates to contribution envelopes, which are employed by many 10 churches to be used by their members during a year in making regular Sabbath contributions.

The envelopes which are generally used are dated giving the month, day and year so 15 that each envelope represents a certain Sunday of a year and these envelopes are issued to the church members at the beginning of each year.

It has been found that this method is not 20 entirely satisfactory and is also very expensive because the church must order sufficient quantities of the envelopes, which come in cartons containing fifty two or fifty three envelopes, according to the number of Sundays of a year, to supply each of the present 25 members and to allow for new members coming into the church during the year.

The extra sets or cartons of envelopes are either a partial or total loss, because if they 30 are not used during the year they cannot be used during the following year as they are dated for a specific year. Then again, when a carton is given a new member during the year, all of the envelopes not used prior to 35 the time the carton is accepted by the new member must be destroyed.

It is the object and intention of the present invention to overcome this condition. By reference to the accompanying drawing 40 Figure 1 illustrates an envelope of the twin pocket type having printed thereon "Fiscal Sunday Number 52." The term "Fiscal Sunday" means that it is a Sunday of a fiscal year. Figure 2 shows another envelope having a slightly different phrase, namely, 45 "14th Sunday of our Fiscal year"—printed thereon.

These phrases are preferably printed on each envelope, so that a phrase will be on each pocket, and as shown in Figure 1, the 50 printed matter appears twice. Of course, when a single or three pocket envelope is employed the phrase will occur on the envelope as often as there are pockets.

With a set of fifty-two or fifty-three envelopes, each representing a Sunday of a year, and consecutively numbered, it is evident that the fiscal year may begin with any month of the year and any Sunday. If when ordering, a greater supply is ordered than 55 is issued to the congregation during the year, the sets of envelopes remaining may be used for the next or succeeding year.

Should the envelopes be issued to all of the parishioners for a year beginning with 60 the first Sunday in the month of May, and later on new members become affiliated with the church and desire a set or package of envelopes, a set could be furnished and the 65 year for this member begun with the Sunday 70 following the issuance of the set of envelopes.

With envelopes having these phrases it is possible to print them in greater quantities 75 so that the churches may be furnished with as large or as small a supply as desired at any time, and at a greatly reduced cost than is possible with the present method of printing. It has been determined that a saving 80 in the costs will range from 25% to 40% according to the size of the order, or number of sets of envelopes ordered.

Having described my invention what I claim as new and desire to secure by Letters Patent is:

A package or set of contribution envelopes including a number of envelopes representing the Sundays of a fiscal year, and each envelope consecutively numbered to correspond to the Sundays of the fiscal year.

LYMAN R. SWETT.
